BATTERY TERMINAL CONNECTER

Joseph M. Pulici, Hawley, Pa.

Application February 2, 1935, Serial No. 4,703

1 Claim. (Cl. 173—259)

This invention relates to improvements in a battery terminal connector, and it is primarily an object of the invention to provide a connector of this kind wherein there is not less than a 5 ninety percent contact between the socket member of the connector and the battery post with which such socket member is adapted to be engaged.

Another object of the invention is to provide 10 a connector of this kind comprising a socket member of a split type together with an arcuate key for coaction with said socket member to maintain the desired clamping action of the socket member upon the terminal post of a battery and in a manner whereby liability of accidental displacement of the key is substantially 15 eliminated.

The invention also has for an object to provide 20 a connector of this kind comprising a split socket member for engagement with the terminal post of a battery together with a key for coaction with the split socket member to maintain the same in desired clamping engagement with the post, said key and its engagement with the socket member 25 being such as to substantially eliminate liability of accidental displacement of the key and which preferably requires impacts upon the key to effect a release of the socket member.

The invention consists in the details of construction and in the combination and arrangement of the several parts of my improved battery terminal connector whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better 40 understood, I will now proceed to describe the same with reference to the accompanying drawing, wherein:—

Figure 1 is a view in top plan illustrating a 45 connector constructed in accordance with an embodiment of my invention and in clamping engagement with the terminal post of a battery:

Figure 2 is a view in side elevation of the structure as illustrated in Figure 1;

Figure 3 is a sectional view taken substantially 50 on the line 3—3 of Figure 2.

As illustrated in the accompanying drawing, P denotes a conventional type of battery terminal post with which my improved connector C is adapted to be employed. As herein disclosed my 55 connector comprises a split socket member I pos-

sessing a certain degree of inherent resiliency whereby the same may be effectively clamped in close contact with the post P. The extremities of the socket member at the split ends thereof are continued somewhat to provide extensions or 5 arms 2. The opposed faces of these arms 2 are in relatively close proximity so that, as clearly illustrated in Figure 1, when the connector is in applied or effective position upon the post P the socket member I will have close contact of not 10 less than ninety percent with the post P.

Substantially diametrically opposed to the split, the socket member I carries a supplemental socket 15 of any preferred type and which is adapted to receive and have electrical connection with the bared end portion 5 of a conventional cable A.

The outer side face of each of the extensions or arms 2 of the socket member I is provided entirely thereacross with a groove or channel 6 open at both ends and disposed on an arc of a 20 circle. Both of these grooves or channels are scribed about substantially a common center. The base walls 6a of these grooves or channels 6 are disposed in convergence and from the top 25 and bottom as illustrated in the accompanying drawing so that upon application of the key K to be hereinafter more particularly referred to, the extensions or arms 2 will be retracted one toward the other sufficiently to effect the desired 30 close contact of the socket member I with the post P.

As clearly illustrated in the accompanying drawing, the key K is substantially U-shaped in form and has its side arms 7 disposed lengthwise on a curvature similar to the curvature of the 35 grooves or channels 6 of the extensions or arms 2 hereinbefore referred to. The opposed or inner edges of the side arms 7 are also in divergence and, as particularly illustrated in Figure 3, from 40 a point immediately adjacent to the cross member 8 of the key to the outer ends of the side arms 7. The angle of divergence of these inner edges of the arms 7 is also substantially the same 45 as the angle of divergence of the base walls 6a of the grooves or channels 6.

With the key K removed or with the arms 7 of the key only slightly engaged within the grooves 6 of the socket member I, said socket member will be sufficiently expanded to allow the same to be disposed around the post P. By imposing suitable impacts upon the outer cross member 8 of the key K said side arms will be forced inwardly of the grooves or channels 6 in a direction lengthwise of the side arms 7 and the coaction of the inner edges of said arms 7 with 55

- the base walls 6^a of the grooves 6 will result in contraction of the socket member 1 resulting in the same being brought into effective close or clamping engagement with the post P and with not less than ninety percent of the terminal wall of the socket member 1 in direct contact with the peripheral surface of the post P thus assuring a connection of maximum efficiency.
- 10 The curvature of the arms 7 of the key K and the coaction of the same within the grooves 6 provide means which effectively prevents accidental displacement of the key and particularly as a result of the vibrations incident to the travel of a vehicle carrying my improved connector.
- 15 This coaction of the key K with the socket member 1 also substantially prevents removal of the key by a direct pull. It has been found in practice that the most effective way to remove the key when it is desired to disengage the connector from the post P is to impose a series of impacts upon the connecting member 8 of the key so as to cause said key to retract in a circular path of travel.

20 From the foregoing description it is thought to be obvious that a battery terminal connector constructed in accordance with my invention is particularly well adapted for use by reason of the convenience and facility with which it may

be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

10 I claim:—

A terminal connector of the class described comprising a split ring with arms extending from the ends of the ring, arcuate grooves extending across the outer side faces of the arms, the outer side of the grooves being disposed toward the ring, and a key having arcuate side arms, said arms being disposed lengthwise on a curvature of a radius similar to the radii of the curvature of the grooves in the outer side faces of the arms, said side arms of the key snugly engaging within the grooves of the arms of the connector with the inner edges of the side arms of the key having close contact with the base walls of the grooves, the base walls of the grooves being in convergence toward the top faces of the arms and the inner edges of the side arms of the key diverging toward their outer ends.

25 JOSEPH M. PULICI.
